LAWN MOWER HOUSING

Clifford Brooks Stevens, Milwaukee, Wis., assignor to
Outboard Marine Corporation, Waukegan, Ill., a
corporation of Delaware

Original design application Apr. 27, 1962, Ser. No.
69,882. Divided and this application Sept. 20, 1963,
Ser. No. 77,734

Term of patent 14 years

(Cl. D40—1)

Fig. 6.

FIGURE 1 is a perspective view showing the top, front, and one side of a first embodiment of a lawn mower housing incorporating my design;

FIGURE 2 is a perspective view showing the top, rear, and other side of the lawn mower housing shown in FIGURE 1;

FIGURE 3 is a perspective view showing the top, front, and other side of the lawn mower housing shown in FIGURE 1;

FIGURE 4 is a perspective view showing the bottom, front, and other side of the lawn mower housing shown in FIGURES 1 and 5;

FIGURE 5 is a perspective view showing the top, front, and other side of a second embodiment of a lawn mower housing incorporating my design; and

FIGURE 6 is a perspective view of the top, rear, and other side of the lawn mower housing shown in FIGURE 5.

The broken line representation of a motor and wheels in FIGURE 1 is for the purpose of illustration only.

This application is a division of my copending application Serial No. D. 69,882, filed April 27, 1962.

I claim:

The ornamental design for a lawn mower housing, as shown and described.
